VENDING MACHINE

Marcus L. Holt, Lookout Mountain, Ga., assignor
of one-half to John B. Brock, Adairsville, Ga.

Application October 5, 1944, Serial No. 557,281

13 Claims. (CL. 312—48)

1

The present invention relates to vending machines, and is particularly concerned with vending machines of the coin controlled type, particularly adapted to be used for vending bottled goods, such as beverages.

The vending machine, however, is capable of handling various type of merchandise packed in a round container, and in some embodiments of the invention might be adapted for the vending of canned goods.

One of the objects of the invention is the provision of an improved vending machine structure adapted to facilitate the packing of a maximum number of articles to be vended in a minimum space and in such manner that the articles may be discharged subject to the control of a coin controlled device, one by one, with a minimum amount of wear and tear or breakage of the articles to be vended.

Another object of the invention is the provision of an improved construction of a vending machine for bottled goods of the type in which the bottles are stacked in substantially horizontal position in a pair of vertically extending series, the bottles of each series being offset vertically with respect to the bottles of the other series, and the bottles of each series extending into the spaces between the bottles of the other series in such manner that bottles are withdrawn alternately from each of the series at the bottom, and the entire two series of bottles are all controlled by the lowermost bottle of one of the series at any particular time.

Another object of the invention is the provision of an improved vending machine for bottled goods of the class described in which the bottles are maintained out of contact with each other so that the bottles do not rub against each other and so that the printed matter, such as the name of the manufacturer, trade-marks, etc. on the bottles will not be marred or destroyed, as may be the case in some of the devices of the prior art.

Another object of the invention is the provision of an improved vending machine of the class described which requires a minimum amount of time and effort in the loading of the machine, which is simple, which may be economically manufactured, and which may be manufactured in a unit form so that the capacity of any installation may merely depend upon the number of units that are used in the installation.

Another object of the invention is the provision of an improved vending machine of the class described, the operation of which is certain and dependable so that there is no possibility of

2

the vendee getting more than one bottle for each coin deposited and so that the vendee is also assured of getting the merchandise for which he has made his deposit.

Another object is the provision of an improved vending machine for bottled goods in which the major portion of the weight of the bottles which are arranged in two columns, is supported by virtue of the friction with the vertical guides and by a horizontal swinging spacer so that the discharge of all the bottles in the two columns is controlled by the lowermost bottle but there is a minimum amount of weight or pressure on any bottle which minimizes the possibility of breakage.

Other objects and advantages of the invention will be apparent from the following description and the accompanying drawings, in which similar characters of reference indicate similar parts throughout the several views.

Referring to the four sheets of drawings accompanying this specification,

Fig. 1 is a side elevational view of a vending machine embodying the invention;

Fig. 2 is a fragmentary rear elevational view, showing the lower part of the vending machine;

Fig. 3 is a front elevational view, with part of the mechanism broken away, to omit repetition of the same structure;

Fig. 4 is a sectional view, taken on the plane of the line 4—4 of Fig. 1, looking in the direction of the arrows;

Fig. 5 is a fragmentary sectional view, taken on the plane of the line 5—5 of Fig. 4, looking in the direction of the arrows.

The vending machine is preferably supported upon a supporting frame, which is indicated in its entirety by the numeral 10. This mechanism may consist of a bottom frame, which is substantially rectangular in side elevation and front elevation, and which consists of a plurality of angle iron frame members suitably welded or otherwise secured together.

Thus, the base frame consists of a pair of horizontal angle irons 11, 12, joined together at the front by a transverse angle iron 13, and at the back by a transverse frame member 14 (Fig. 4), forming the upper part of the base frame.

This base frame is supported by depending angle iron legs 15 to 18, which extend downwardly at right angles to the top frame members 11 to 14, and are also welded to them. Two forward legs 15 and 18 may be joined by a brace plate 19 located below the trough 20, from which the bottles are discharged.

The front and rear legs on each side, such as the legs 15, 16, and 17, 18, are joined by side plates 21, 22 secured to the legs by welding or other fastening means, and aiding in defining the trough member 20.

The trough member 20 may consist of a sheet metal member bent to substantially U-shape and increasing in depth from the back toward the front so that the trough slopes sufficiently to cause the bottles to drop out by gravity. The sheet metal trough 20 is preferably covered on its lower side with a layer of sheet rubber 23 secured to the trough by suitable screw bolts and projecting forwardly beyond the trough at 24 in substantially U-shape, to provide a non-metallic continuation of the trough for deadening sound, and permitting the discharge of the bottles with a minimum amount of noise.

The metal lining of the trough gives the trough a minimum amount of friction so that the bottles are quickly impelled out of the discharge opening 25 in the front of the base frame by gravity.

The angle irons which form the rear legs 16, 17 may extend above the base frame and form a part of the upper frame, which comprises the supporting and guiding mechanism for the bottles. Thus the legs 16, 17 extend to the top of the frame, where they are joined by a transverse frame member 26 to another vertically extending angle iron frame member 27 or 28, one being on each side of the structure, to form an upper framework which is also substantially rectangular in plan and side elevation.

At the top the upper frame members 26 are joined by transverse frame bars 29, 30 that are secured to the frame members 26 by screw bolts or other convenient fastening means so that an open, rigid framework is provided for supporting the bottles. This open framework is preferably provided at predetermined points with additional guides for engaging and guiding the bottles, such as, for example, the vertical guide rods 31, 31, which engage the cap of the bottle, and the vertical guide rods 32, 32, which engage the outside of each bottle adjacent the neck.

Other guide members which are preferably provided are the vertical guide rods 33, 33 carried by the frame members 27, 28 for engaging the side of the bottle, preferably at its restriction, near the bottom, and the guide rods 34, 34, which engage the ends of the bottles.

The frame of the mechanism is preferably made of steel or other suitable material, but the guide rods are preferably made of softer material, such as brass, which is adapted to produce a minimum amount of abrasion on the bottles.

In order to support the guide rods 31, 32, the corner frame members 16, 17 may be provided with a plurality of angular brackets 35, 38. The angular brackets 35 may be welded or bolted to the frame member 16 and the brackets 38 may be welded or bolted to the frame member 17. Referring to Fig. 4, it can be seen that the bracket 35 has supporting flanges 36, 37 which extend at right angles to each other. The bracket 38 has a similar construction. The brackets 35, 38 support the rods 31, 32 in proper position, the rods being welded to the brackets. At the upper end of the framework a bracket 95 is provided (Fig. 1) to support the upper ends of the rods 31, 32, the rods being welded to the bracket. The bracket 95 is welded to a transverse support member 29 which is bolted to the transverse frame member 26.

At the lower ends of the rods 31, 32, a substantially inverted U-shaped bracket 96 is provided

for supporting the lower ends of the rods 31, 32 and providing a means for securing them to the corner frame members 16, 17. The upper horizontal flange portion of bracket 96 is substantially E-shaped. The center leg portion of the E-shaped flange of the bracket 96 is provided so that the angular bracket 55 can be bolted thereto and in turn the bracket 55 is fastened to the bearing strip 52 of the frame member 50 to support the same.

The guide rods 33, which engage the convex side of the bottles of each series on the outside of the assembly, may be pinned or welded to the adjacent flanges of the frame members 27, 28.

In order to provide for the loading of the mechanism, the guide rods 34 are movably supported in such manner that they have two positions, one in which they engage the ends of the bottles, and the other in which they are pivoted outward so that the bottles may be replaced from the front end of the machine.

For this purpose each guide rod 34 is welded or otherwise secured to a vertical angle iron frame member 40, which in turn is pivotally mounted on a pair of links 41, one link being disposed at the upper end, and another at the lower end, as shown in Fig. 3.

The links 41 are pivotally mounted on the angle iron brackets 42, which are carried by the upper frame members 11, 12 of the base. At the upper end the links 41 are pivoted upon gooseneck frame members 42', each of which has an attaching flange 43 secured to one of the vertical frame members 27 or 28.

Goose-neck brackets 42' extend upward and downward in substantially U-shape, and the depending leg 44 pivotally supports the upper link 41. The U-shape of the bracket 42' provides sufficient room for the frame members 40 and guide rods 34 to pivot upward and pass over until these members reach the dotted line position of Fig. 3, in which the framework is open, to replace the bottles from the front end of the machine.

The spacing between the guides 31 and the guides 34 is sufficient to permit these members to engage the two ends of the bottles with a suitable clearance so that the bottles may slide freely and downwardly in the frame when released by the mechanism.

The spacing between the guide members 32, 33 on one side and guide members 32, 33 on the other side is such that the bottles in the respective series will assume a position so that when the bottles are engaging the pivotal supporting members 45 interposed between each pair of bottles, the spacing between the supporting member 45 and guides 32 and 33 for each bottle is sufficient to prevent the bottle from passing downward until it is properly released.

Thus the lowermost bottle 46 (Fig. 2) rests on the lowermost supporting member 45, and in turn is engaged on its upper right side by another supporting member 45, which in turn is engaged on its right upper side by the second bottle 48a.

The supporting members 45 may all be similar in shape, and they are preferably pivotally supported on the framework. For this purpose the framework is provided with a top frame member 47, which is secured to the cross bars 29, 30 by welding or bolting, and which has the depending angle irons 48, 49.

The angle irons 48, 49 each carries a vertically extending bar or frame member 50, 51 provided with a bearing member 52, 53, comprising a strip of brass or steel, which is provided with apertures

54, as shown in Fig. 5, serving as bearings for the trunnions which are formed by the ends of each supporting member 45.

The bars 50, 51 confine the supporting members 45 against axial movement, and the bearing strips 52, 53 provide for the pivotal movement of the supporting members 45.

The vertical frame members 50, 51 are also secured to the frame at their lower ends, such as, for example, frame member 51 and its bearing strip 53 may be secured at the bottom to the front angle iron 13 by means of a suitable bolt.

The frame member 50 and its bearing strip 52 may be secured to the central leg of the E-shaped horizontal flange of bracket 96 by means of suitable bolts and the angle bracket 55.

The pivoted supporting members 45 are located midway between the lateral guides 32, 33 and 32, 33, and, as all of these supporting members are similar in shape, only one need be described. Each supporting member is preferably constructed of a rod of brass or other suitable metal, such as steel, having a straight central portion 56, which is covered with a non-metallic cushion 57, such as a rubber tube, and which is adapted to engage and support the bottles.

At the front end, which is adjacent the bottom of the bottle, each rod forming the pivoted supporting members 45 is bent upward at an obtuse angle, forming a crank portion 58, which is again bent longitudinally to form a trunnion 59, which is pivotally mounted in the bearing strip 53.

At the other end of the straight portion 56, the rod is bent upward at an obtuse angle, providing a diagonally extending crank portion 60 located adjacent the neck of the bottle. This diagonal crank portion 60 is again bent laterally adjacent the top of the neck, and the end portion 61 of the rod is located in the same axis as the trunnion 59, forming another trunnion at that end of the rod for engagement in the bearings of the bearing strip 52.

The bearings in these strips are spaced vertically sufficiently so that the pivoted supporting members 45 may be located as shown in Fig. 2 when the mechanism is loaded with bottles.

All of the pivoted supporting members 45, except the lowermost one, indicated at 45a, terminate inside of the frame members 50, 51, but the pivoted supporting member 45a has its left trunnion (Fig. 1) elongated or extended through a bore 62 in the frame member 50 and beyond this bore, to provide a support for a latching member 63, which controls the descent of all of the bottles.

The latching member 63 comprises a flat rectangular plate of metal, which is provided with a centrally located bore and with a hub 64 welded to the plate at said bore.

The hub 64 has a set screw 65, by means of which the latching member 63 may be fixedly secured to the shaft 45a of the first or lowermost pivoted supporting member 45. The latching member 63 is provided with the convexly curved lower and upper edges 66, 67, which are formed with the spaced grooves 68, 69, 70, and 71. Only two of these grooves at one end of the latching member 63 may be used at one time, but the spacing between the grooves 68, 69 and grooves 70, 71 may be varied so that the latter are adapted to handle bottles of different size or shape.

The grooves 68 to 71 are adapted to receive the roller 72, which is carried by the cross-head 73 located on the upper end of a plunger 74, which forms the armature of a solenoid. The grooves 68 to 71 are preferably slightly larger in a lateral

direction than the roller 72 so as to provide a clearance, to assure the roller entering into one of the grooves upon upward movement of the plunger.

5 The cross-head 73 is preferably constructed of non-magnetic metal, while the roller 72 may be constructed of steel, and it is rotatably mounted upon a pin 75 carried by the upwardly extending legs 76 of the cross-head 73.

10 The cross-head 73 is secured to a laminated plunger 74 by means of a transverse through bolt 77, the cross-head having an apertured tongue 78, which is located between the upwardly extending halves 79 on the plunger 74. The plunger is built up of a plurality of thin laminations of soft iron or metal of magnetic qualities, and it may be provided at its lower end with an axially extending brass guide rod 80, which is slidably received in a bore 81 in the laminated flux carrying member 82.

20 The laminated flux carrying member 82 is preferably of the closed type, and also comprises a multiplicity of laminations of magnetic metal, such as soft iron, forming a substantially rectangular frame with a central opening 83 for receiving the solenoid coils 84.

The solenoid coils are provided with a vertically extending bore, which they surround, and which is adapted to receive the armature or plunger 74.

30 A compression spring 85 is compressed between a shoulder 86 on the armature and the upper end of the core 82, urging the plunger to the position in which it is shown in Fig. 2. When the coils of the solenoid are energized, the plunger is pulled downwardly, pulling the roller 72 out of one of the grooves 68 or 69.

The solenoid core 82 and its associated parts are all preferably mounted upon a supporting plate 87, which in turn is carried by the transverse lower rear frame member 14.

40 The mechanism is preferably provided on its forward side with a suitable coin control 88 in the form of a housing having a coin actuated switch and a slot 89 for receiving coins. A coin dropped in the slot 89 passes down a guide 90 and engages a pivoted switch lever 91, which it pivots in a clockwise direction to close contacts to which the conductors 92, 93 are connected.

45 The conductors 92, 93 lead to the solenoid coils 84. The arrangement of the switch lever 91 is preferably such that contact is momentarily made as the coin passes, after which the coin is permitted to pass by the lever 91, and then the lever, which is urged upwardly by a suitable coil spring 94, returns to its position, blocking the guide 90. Various types of coin controlled switches may be employed with my mechanism, and I desire it to be understood that I do not wish to be limited to any particular type of coin actuated switch.

50 The operation of my coin controlled vending machine is as follows: The machine may be loaded by moving the end frame members 49 and their guides 34 from the full line position of Fig. 3 to the dotted line position, which opens the end 65 of the frame. The lowermost pivoted supporting member 45a may then be either in the left or the right position; but assuming it to be in the position of Fig. 2, looking at the rear of the machine, the cushion 57 on the straight portion 56 of this

60 supporting member is located to engage the lower right hand side of the bottle 46, and it is held in this position by the engagement of the plunger roller 72 in the slot 69.

65 Normally, all of the other pivoted supporting members 45 tend to hang downwardly due to

gravity, and are located in a central position when there are no bottles located between them, but when the bottle 46 is inserted in Fig. 2, the lowermost supporting member which has been previously manually moved to the left supports and contacts the lower right hand portion of the bottle 46, and, therefore, the shape and contour of the bottle 46 causes the next supporting member 45 above said lowermost supporting member to move slightly to the right and contact the upper right hand portion of bottle 46 and the lower left hand portion of the bottle 46a to support the same.

When the next bottle 46a is inserted, it will be found that the cushion of one of the members 45 is located above the center of bottle 46 and below the center of bottle 46a so that the bottle 46a cannot pass downward. Removal of the bottle 46 will automatically permit the cushion of this supporting member to pivot toward the left in Fig. 2, to let the bottle 46a descend. Until the lowermost bottle 46 is removed, the next upper bottle and all others are held in their stacked condition.

In loading the machine thereafter, bottles are inserted alternately in the right and the left hand stacks, each bottle resting upon a cushion 57, which cushion, being pivotally supported, rests upon the next bottle below it in the other stack.

The cushioned supporting members are stabilized by the insertion of the bottles, and the bottles are stacked in such manner that they may be removed alternately from one series or the other by control of the lowermost pivoted supporting member 45.

When loading has been completed, the end guide members 34 are again pivoted over from the dotted line position of Fig. 3 to the full line position, to confine all of the bottles in the framework.

When a purchaser desires to secure a bottle from the vending machine, a coin, such as, for example, a nickel, may be dropped in the slot 89. This coin engages the switch lever 91 against the tension of a light spring 94, moving the switch lever to the closed position, after which the coin is passed into a coin box, and the switch lever returns to its open position.

The momentary closing of the contacts by the switch lever 91 closes an electric circuit, which includes a suitable source of electromotive force for the coils 84 of the solenoid, such as, for example, an 11 volt source, which may be connected in the circuit in series with the solenoid coils 84 and switch contacts of the switch 91.

Momentary closing of the electric circuit energizes the solenoid coils, which generate a magnetic flux in the core 82 that passes through the plunger 74. The plunger 74 is momentarily drawn downward to a central position in the core 82, being guided by rod 80 in bore 81.

Each bottle 46a tends to slide downward, due to gravity, and tends to cam the pivoted supporting member upon which it rests, away from the bottle in question, so that the bottle may pass by the supporting member, but each of the cushioned portions 57 of these supporting members is restrained against such movement by the bottle below it.

The lowermost cushion portion 57 of supporting member 45 is restrained in its position in Fig. 2 only by the latching plate 63 and plunger roller 72.

When the plunger is momentarily withdrawn, the lowermost supporting member 45 is pivoted counterclockwise in Fig. 2 until the lowermost bottle 46 passes the cushion portion 57 of this

supporting member. At the same time the latching plate 63 is pivoted over to a position in which the groove 68 registers with plunger roller 72; and as the plunger is immediately returned to its upper position by the spring 85, the roller 72 becomes engaged in the groove 68.

As the lowermost bottle 46 drops into the trough 20 and its pivoted supporting member 45 moves toward the right in Fig. 2, there is nothing to restrain the next supporting member 45a and its pivots toward the left, releasing the next bottle 46a, which drops down on the lowermost supporting member 45 that is now latched in its right hand position by means of plunger roller 72 in the slot 68.

At the same time all of the other supporting members 45 have their cushion portions 57 pivoted over to the opposite position, passing one bottle; and thereafter the bottles assume a similar position, but all the bottles are one step lower in the series.

When the next coin is dropped and the solenoid is energized and the plunger is withdrawn, the process is repeated, bottle 46a being dropped into the trough, and the latching member 63 returns to the position of Fig. 2.

Thus bottles are alternately dropped from one and then the other series of bottles, but the bottles are kept out of contact with each other and engage only the metal guides and the cushioned portions of the pivoted supporting members 45.

The pivoted supporting members 45 may also have their crank portions 58 cushioned with rubber tubes, if this portion tends to strike the bottom of the bottle; but in other embodiments of the invention the crank portion 58 may be located so that it will not engage the bottom of the bottle.

It will thus be observed that I have invented an improved vending machine for bottled merchandise, such as beverages, which is simple in construction and which is adapted to handle the bottles without possibility of marring or wearing off the printed matter which is impressed upon the glass of the bottle.

The mechanism also protects the labels and printed matter which is applied to bottles in the form of stickers.

The present device may be constructed in any number of units, which may be placed side by side in the refrigeration compartment of a suitable cabinet, and this mechanism is adapted to receive a maximum number of bottles in a minimum amount of space.

The mechanism is simple, positive, and while it assures the purchaser of securing a merchandise unit for each coin, it also prevents the users from getting more than one bottle for any coin. The structure of the mechanism is adapted to be manufactured at a low cost due to the great simplicity of the mechanism by means of which electric motors, revolving cams, endless chains, metal pockets, gear reducers, etc., of the prior art devices are eliminated. Thus, the present invention greatly reduces the original cost of the vending machine and it may be operated at a much lower cost than the devices of the prior art by virtue of the small amount of electricity consumed in the momentary operation of the solenoid switch as compared with the driving of electric motors in the devices of the prior art.

While I have illustrated a preferred embodiment of my invention, many modifications may be made without departing from the spirit of the invention, and I do not wish to be limited to the

precise details of construction set forth, but desire to avail myself of all changes within the scope of the appended claims.

Having thus described by invention, what I claim as new and desire to secure by Letters Patent of the United States, is:

1. In a vending machine for bottled merchandise, the combination of means for guiding and maintaining the alignment of two stacks of bottles by engagement on three of the sides of said bottles, spacing means located between the bottles of adjacent stacks, the bottles in the two stacks being offset vertically from each other, supporting means for the lowermost bottle in one stack or the other, depending upon the position of said supporting means, coin controlled means for controlling the position of said supporting means, whereby the supporting means may be released to move laterally into position to hold the lowermost bottle in one stack while releasing the lowermost bottle in the other stack.

2. In a vending machine for articles having an external surface circular in cross section, the combination of a supporting frame with a plurality of upwardly and downwardly extending guides for engaging the outer sides of a plurality of stacks of the said articles, the articles to be vended being arranged in a pair of upwardly and downwardly extending series, with the articles staggered vertically in one stack with respect to the articles in the other stack, movably mounted bail-shaped spacing members carried by said frame, said spacing members being located between the articles of one stack or series and the articles of the other stack or series, and a bail-shaped support member having horizontally extending trunnions pivotally mounted in the frame and located below the center of the lowermost article in one of said stacks and adapted to provide a support for said lowermost article, which in turn supports the articles of both stacks through the intermediary of said spacing members, and coin-controlled means releasing for movement said support member from a position where it supports the lowermost article of one stack to a position where it supports the lowermost article of the other stack, one article being dropped from the lowermost stack at every movement of said support member, and all of the other articles moving downward one step at each movement of said support member.

3. In a vending machine for articles having an external surface circular in cross section, the combination of a supporting frame with a plurality of upwardly and downwardly extending guides for engaging the outer sides of a plurality of stacks of the said articles, the articles to be vended being arranged in a pair of upwardly and downwardly extending series, with the articles staggered vertically in one stack with respect to the articles in the other stack, movably mounted bail-shaped spacing members carried by said frame, said spacing members being located between the articles of one stack or series and the articles of the other stack or series, and a bail-shaped support member having horizontally extending trunnions pivotally mounted in the frame and located below the center of the lowermost article in one of said stacks and adapted to provide a support for said lowermost article, which in turn supports the articles of both stacks through the intermediary of said spacing members, and coin-controlled means releasing for movement said support member from a position where it supports the lowermost article of one

stack to a position where it supports the lowermost article of the other stack, one article being dropped from the lowermost stack at every movement of said support member, and all of the other articles moving downward one step at each movement of said support member, said movable spacing members comprising a plurality of pivotally mounted bail-shaped transverse members carried by said frame.

10 4. In a vending machine for articles having an external surface circular in cross section, the combination of a supporting frame with a plurality of upwardly and downwardly extending guides for engaging the outer sides of a plurality of stacks of the said articles, the articles to be vended being arranged in a pair of upwardly and downwardly extending series, with the articles staggered vertically in one stack with respect to the articles in the other stack, movably mounted bail-shaped spacing members carried by said frame, said spacing members being located between the articles of one stack or series and the articles of the other stack or series, and a bail-shaped support member having horizontally extending trunnions pivotally mounted in the frame and located below the center of the lowermost article in one of said stacks and adapted to provide a support for said lowermost article, which in turn supports the articles of both stacks through the intermediary of said spacing members, and coin-controlled means releasing for movement said support member from a position where it supports the lowermost article of one stack to a position where it supports the lowermost article of the other stack, one article being dropped from the lowermost stack at every movement of said support member, and all of the other articles moving downward one step at each movement of said support member, said support member comprising a transverse member carried by cranks and trunnions, a latching member, and electrically actuated means to control the position of said latching member, said latching member being elongated and fixed to one of said trunnions and having grooves for engagement by the electrically actuated means.

5. In an article vending machine, the combination comprising guides defining a section through which said article normally gravitates from top to bottom, said section being of a width to hold a plurality of series of the articles vertically aligned in displaced relationship laterally of the section, spacing members disposed in a row extending longitudinally in the mid-portion of the section, said spacing members being separated from one another in the row so as to lie between adjacent articles in said series to separate said articles and maintain the articles of one series in staggered relationship to those of the other, means supporting said spacing members for movement laterally of the section a distance sufficient to allow alternate passage of the articles of said series across opposite sides of the spacing members, and means for alternately retaining the lowermost one of said spacing members in a supporting position under one or the other of said series, whereby said lowermost one of the spacing members normally retains the articles in said section and releases one of said articles upon each movement from a position below one of the series to a position below the other series.

6. In a vending machine for articles of circular section, the combination comprising guides defining a section through which said articles normally gravitate from top to bottom, said section

being of a width to hold a plurality of series of said articles vertically aligned in displaced relationship laterally of the section, spacing members disposed in a row extending longitudinally in the mid-portion of the section, said spacing members being separated from one another in the row by distances less than the diameter of one of said articles and greater than one-half of said diameter and said spacing members having an outer diameter greater than the lateral displacement of the articles of the series so that they lie between adjacent articles in said series to separate them and maintain the articles of one series in staggered relationship to those of the other, means for supporting said spacing members for movement laterally of the section a distance sufficient to allow passage of the articles through the section on successive alternate sides of the spacing members, and means for alternately releasing the lowermost articles of the series from the section.

7. In a vending machine for articles of circular section, the combination comprising guides defining a section through which said articles normally gravitate from top to bottom, said sections being of a width to hold a plurality of series of said articles vertically aligned in displaced relationship laterally of the section, spacing members disposed in a row extending longitudinally in the mid-portion of the section, said spacing members having article separating portions of a diameter greater than the lateral displacement of the articles of the series so that they normally lie between adjacent articles in said series to separate them and maintain the articles in one series in staggered relationship to those of the other, and means for supporting said spacing members for movement laterally of the section a distance sufficient to allow passage of the articles through the section on successive alternate sides of the spacing members.

8. A controlling mechanism for a vending machine for articles round in cross section, comprising a supporting frame having a plurality of guides for guiding two series of the articles vertically aligned and with the articles of the series in staggered relationship to each other, the articles of one series being located at an elevation which is between the elevations of the articles of the other series, vertical frame members secured to said supporting frame, spacing members movably mounted on said frame members and having portions located between the articles of both series to prevent articles of one series from engaging the articles of the other series, and movable means for supporting the lowermost article in the series so that both series are supported therefrom through the spacing members, and coin-controlled means for effecting a release of said movable means to effect release of the lowermost article of either one of said series responsive to the placing of a coin.

9. A controlling mechanism for a vending machine for articles round in cross section, comprising a supporting frame having a plurality of guides for guiding two series of the articles vertically aligned and with the articles of the series in staggered relationship to each other, the articles of one series being located at an elevation which is between the elevations of the articles of the other series, vertical frame members secured to said supporting frame, spacing members movably mounted on said frame members and having portions located between the articles of both series to prevent articles of one series from en-

gaging the articles of the other series, and movable means for supporting the lowermost article in the series so that both series are supported therefrom through the spacing members, and coin-controlled means for effecting a release of said movable means to effect release of the lowermost article of either one of said series responsive to the placing of a coin, said portions of the spacing members being covered with soft, resilient cushions for engaging the articles and preventing their being marred or damaged during their course through the machine.

10. A controlling mechanism for a vending machine for articles round in cross section, comprising a supporting frame having a plurality of guides for guiding two series of the articles vertically aligned and with the articles of the series in staggered relationship to each other, the articles of one series being located at an elevation which is between the elevations of the articles of the other series, vertical frame members secured to said supporting frame, spacing members movably mounted on said frame members and having portions located between the articles of both series to prevent articles of one series from engaging the articles of the other series, and movable means for supporting the lowermost article in the series so that both series are supported therefrom through the spacing members, and coin-controlled means for effecting a release of said movable means to effect release of the lowermost article of either one of said series responsive to the placing of a coin, a supporting member for the lowermost of the articles in either one of said series, said movable means comprising a member pivotally carried by said vertical frame members and having a supporting portion mounted on a crank, a latching member for controlling the movement of said crank, said latching member having two positions, and electromagnetically actuated means for engaging and holding said latching member in either of its two positions, said latching member being fixed to said movable means and having grooves for engagement by the electromagnetically actuated means.

11. A release mechanism for releasing articles round in cross section from a vending machine having a supply of said articles supported by the lowermost of said articles in a stack, comprising a supporting frame, guide means mounted on said frame to confine the movement of the articles to be vended in a predetermined path, a bail-shaped support member having horizontally extending trunnions pivotally supported by said frame and engaging the lowermost article to be vended so as normally to prevent movement and restrain the discharge of said article from the vending machine, a latching member, said latching member being elongated and fixed to one of said trunnions of said support member and having a plurality of grooves in one end thereof, and an electrically actuated keeper for said latching member comprising a rod having an end normally engaging one of said grooves in the end of the latching member whereby the actuation of said keeper releases said latching member to permit said support member to be cammed by the lowermost article to a second position to release the said lowermost article from the vending machine.

12. A release mechanism for releasing articles round in cross section from a vending machine having a supply of said articles supported by the lowermost of said articles in a stack, comprising

a supporting frame, guide means secured to said frame to confine the movement of the articles to be vended in a predetermined path, a bail-shaped support member having horizontally extending trunnions pivotally supported by said frame and engaging the lowermost article to be vended so as normally to prevent movement and restrain the discharge of said article from the vending machine, a latching member, said latching member fixed to one of said trunnions of said support member and having a plurality of grooves therein, an electrically actuated keeper for said latching member comprising a rod having a portion normally engaging one of said grooves in the latching member whereby the actuation of said keeper releases said latching member to permit said support member to be cammed by said lowermost article to a second position to release the said lowermost article from the vending machine, said vending machine accommodating a pair of stacks of the articles and having therein movable retaining elements for maintaining the separation of the stacks as the articles move along the guide means, said movable retaining elements also serving as supporting spacers through which the articles of one stack are supported by the articles in the other stack, and said latching member permitting said support member to support the articles in the second stack when cammed over toward said second position.

13. A release mechanism for releasing articles round in cross section from a vending machine having a supply of said articles supported by the lowermost of said articles in two adjacent stacks, comprising a supporting frame, guide means carried by said frame to confine the movement of

the articles to be vended in a predetermined path, a ball-shaped support member having horizontally extending trunnions pivotally supported by said frame and engaging the lowermost article to be vended so as normally to prevent movement and restrain the discharge of said article from the vending machine, a latching member, said latching member fixed to one of said trunnions of said support member and having a plurality of grooves therein, and an electrically actuated keeper for said latching member comprising a rod having a portion normally engaging one of said grooves in the latching member whereby the actuation of said keeper releases said latching member to permit said support member to be cammed by said lowermost article to a second position to release the said lowermost article from the vending machine, the stacks of articles having their articles disposed in offset positions with respect to elevation, whereby a greater number of articles can be stacked in a limited space, each pair of articles in the two stacks being separated by a bail-shaped spacing member pivotally carried by said frame to prevent contact and marring of one article by the other.

Certificate of Correction

Patent No. 2,438,502.

March 30, 1948.

MARCUS L. HOLT

It is hereby certified that error appears in the printed specification of the above numbered patent requiring correction as follows: Column 14, line 2, claim 13, for the word "ball-shaped" read *bail-shaped*; and that the said Letters Patent should be read with this correction therein that the same may conform to the record of the case in the Patent Office.

Signed and sealed this 25th day of May, A. D. 1948.
